(57) **CLAIM**

The ornamental design for a base for humidifier reservoir for positive airway pressure delivery console, as shown and described.

DESCRIPTION

FIG. 1 is a front, right corner perspective view of a first embodiment of the base for humidifier reservoir for positive airway pressure delivery console according to our new design;

FIG. 2 is right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is another perspective view thereof;

FIG. 9 is a front, right corner perspective view of a second embodiment of the base for humidifier reservoir for positive airway pressure delivery console according to our new design;

FIG. 10 is right side view thereof;

FIG. 11 is a left side view thereof;

FIG. 12 is a top view thereof;

FIG. 13 is a bottom view thereof;

FIG. 14 is a front view thereof;

FIG. 15 is a rear view thereof; and,

FIG. 16 is another perspective view thereof.
